H. C. DIERS

ARTIFICIAL FUEL AND PROCESS OF MAKING THE SAME

Filed March 14, 1921

Henry C. Diers INVENTOR

BY Victor J. Evans

ATTORNEY

WITNESS:

UNITED STATES PATENT OFFICE.

HENRY C. DIERS, OF MARSHFIELD, OREGON, ASSIGNOR OF ONE-FOURTH TO GEORGE A. MARTIN, ONE-FOURTH TO EARL W. MCINTURFF, AND ONE-FOURTH TO WILLIAM T. STOLL, ALL OF MARSHFIELD, OREGON.

ARTIFICIAL FUEL AND PROCESS OF MAKING THE SAME.

Application filed March 14, 1921. Serial No. 452,294.

To all whom it may concern:

Be it known that I, HENRY C. DIERS, a citizen of the United States, residing at Marshfield, in the county of Coos and State 5 of Oregon, have invented new and useful Improvements in Artificial Fuel and Processes of Making the Same, of which the following is a specification.

This invention relates to artificial fuel 10 and processes of making the same and has for its object the provision of a process for making an artificial fuel having the nature of coal from such material as is ordinarily wasted, particularly lignite or the well 15 known soft brown coal which is at present of no value, the process further involving the use of waste wood such as may be found, for example, around saw-mills.

An important and more specific object is 20 the provision of such a process which involves the carbonizing of wood and lignite separately and then mixing them together with a certain percentage of the distillates obtained and subsequently mixing, heating 25 and then compressing the mass which when dry is then broken up.

In carrying out my process I take any 30 desired quantity of waste wood of any kind and lignite and distill them in separate retorts whereby to remove from them the wood tar, coal tar, light oil and the moisture. The carbonized wood, or charcoal and the carbonized lignite are then pulverized 35 by any suitable means and to this powdered material is added a certain percentage of the wood tar and coal tar previously distilled from the wood and lignite. This mixture is thoroughly agitated and is heated in any suitable retort to a temperature of al- 40 most the ignition point. The mass is dis- charged from the heating device, while still very hot, onto a suitably constructed hard bed of very hard material with which co- operates a suitable roller having rolls heat- 45 ed to a temperature of from three hundred and fifty to four hundred degrees Fahrenheit (substantially above the boiling point of water). The mass discharged onto this bed is rolled back and forth by means of 50 the roller until the mixture is formed into a solid homogeneous mass. After each layer is thus rolled a subsequent layer is added

and also rolled and this operation is con- tinued till the desired thickness of the fin- 55 ishished sheet is obtained. In actual practice, this operation is continued until a thickness of one to two feet is obtained. After the mass is cooled it is broken into pieces of suitable size (i. e. of the sizes of ordinary coal) and is then used in exactly the same 60 manner as coal.

The annexed drawing indicates a suitable form of apparatus for carrying out the process, said apparatus forming the sub- 65 ject matter of my copending application 458,138 filed April 2, 1921. Fig. 1 is a dia- grammatic sketch. Fig. 2 shows some de- 70 tails of the same. 10 indicates a grinder of any approved form, which is provided for the purpose of reducing the coal, lignite, 75 wood or other similar material to a finely divided condition. This grinder discharges into the lower end of the elevator 11, which may contain a belt conveyor or the like, not shown. At the upper end, this discharges 75 into a bin, 13, thence into hopper 14, from which the material is elevated by conveyor 15, from which the material drops into the retort 21, which is heated, for instance, by furnace 23, which may be fired by gas in- 80 troduced through pipe 30 or otherwise. Leading from the upper portion of the re- 85 tort is the pipe 28, which conducts the va- pors and gases into the hydraulic main 29. The carbonized material from the retort is 85 discharged into a closed box 31, and may be cooled by a spray from pipe 32. The hori- 90 zontal conveyor 35 carries the material into a grinding device or crusher 37 from which the pulverized material is elevated by the 90 conveyor 38, into the mixing box 40. A suitable binder such as coal tar, wood tar or pitch, is delivered from tank 41 to pipe 42, into the mixing box 40, and the material after being thoroughly mixed is discharged 95 through the chute 43 into the car 44, after which it is dumped upon the bed 45, pro- 100 vided with a heating coil 46, through which steam or the like may be circulated. A roller device, such as a small steam road roller, may then be used to compress the material into a cake. The roller 47 is provided with wide wheels 48, on axles 49, and is operated in the usual manner. The wide wheels or

rollers 48, can be steam heated if desired. The cakes can subsequently be broken up and the finished fuel elevated by the conveyor 50 into the storage tank 51, from 5 which it is discharged through chute 52 into the wagon 53 for delivery to the consumers, or elsewhere.

I have found from experiment that this 10 artificial fuel will burn on the outside of the lump without smoke, in the same manner as anthracite coal or coke. I have also noted that the mass holds together during combustion and that clinkering in the furnace or fire-box is prevented. It is also to 15 be observed that before burning, the artificial material retains its form and integrity under changing climatic conditions even though it is entirely exposed to the weather.

It is of course to be understood that many 20 variations in the percentage of its ingredients may be resorted to but in actual practice I have found that by mixing equal amounts of carbonized lignite and charcoal with about six percent of the distilled mixture of coal tar and wood tar as a binder, I can produce an artificial fuel approximately 25 as good as the best grades of anthracite coal. By varying the proportion of lignite carbon, charcoal and binder I can of course 30 make any grade of fuel desired and having different degrees of hardness, the different grades being adapted for various different purposes as will be of course understood. Another advantage of my process is 35 that the water is removed originally so that none of the heat during combustion is wasted for evaporating the water.

From the foregoing description it will be 40 apparent that I have thus provided a process for producing a highly useful product from material which is ordinarily wasted, my invention thus adding materially to the resources of the country inasmuch as useless matter is convertible into valuable material.

Having thus described my invention what I claim:

1. A slab of artificial fuel consisting of carbonized lignite charcoal and a tar binder, the latter being in such small amount as to 50 make the fuel substantially smokeless when burned, such slab being of great area, whereby it can be subdivided into pieces.

2. A process of making fuel which comprises mixing hot carbonized fuel as coming 55 from a carbonizing retort, and while at near the temperature of ignition, with a tarry binder, and promptly spreading out such mixture on a hard surface and running a hot heavy roller over the same, to simultaneously drive out water vapor, and other vapors, to compress the loose mass into a hard slab and to bond the same, and thereafter subdividing such a slab into pieces of a size convenient for handling.

3. The process of making artificial lump fuel which consists in comminuting carbonized lignite, mixing the same with comminuted charcoal and a binder of tar, heating the same almost to the ignition point, and 70 then rolling the mass with heated rollers into the form of a block, and breaking up the latter.

4. A process of making artificial fuel from carbonaceous matter of organic origin, 75 which comprises destructively distilling the same to form a carbonized mass in the form of relatively small porous pieces, spreading out the carbonized matter while in a highly heated state, mixing with a binder 80 of a tarry nature, and without allowing the same to cool, rolling a hot heavy roller over the same, the active surface of such roller being at a temperature substantially above the boiling point of water, whereby a huge 85 slab of solid fuel is formed, and subdividing this slab into pieces.

In testimony whereof I affix my signature.

HENRY C. DIERS.
